INSECTICIDAL COMPOSITIONS

Kenneth E. Maxwell, Martinez, Calif., assignor
to Shell Development Company, San Francisco,
Calif., a corporation of Delaware

Application May 28, 1942, Serial No. 445,106

6 Claims. (CL-167-43)

1

This invention, a continuation-in-part of my application, Serial No. 409,195, filed September 2, 1941, relates to new and improved insecticidal compositions and more particularly pertains to a new and improved agent for depositing insecticidal material from an aqueous carrier.

A primary object of this invention is to provide an additive for insecticidal compositions capable of yielding increased deposits of said materials when sprayed on foliage, fruits, or dormant trees. Thus, mineral oils, which have long been used as insecticidal sprays, are usually applied in the form of an emulsion with water. For foliage spraying, they are ordinarily emulsified with 96-99% of water, and in dormant spraying with as little as 95% of water. The water acts as a carrying agent for the oil and effects a distribution of the oil over the plant. However, the water also carries considerable quantities of the oil from the sprayed object.

It is towards minimizing the carrying off of the oil and increasing the deposition thereof from an aqueous carrier that the instant invention is directed. It will be obvious that, with increased deposition of the insecticidal material, savings thereof will be effected and a lower concentration of oil in the water will be required to obtain "lethal dosage." A further object is to provide a depositing agent which will cause the insecticide to adhere firmly to the fruit or foliage.

The term "insecticidal material" or "suspensoid" as used herein refers to mineral oils either with or without the addition of toxicants. Such toxicants may comprise pyrethrum, rotenone, derris resins, nicotine, aliphatic thiocyanates, dinitro cresols, dinitro phenols, ketones, ketols, halogenated hydrocarbons such as chlorinated naphthalenes, cresylic acid, alkyl amines, pine oils, etc.

I have discovered that when suitable cation surface-active emulsifiers are added in amounts which do not cause emulsification to an aqueous carrying medium containing an insecticidal suspensoid and this mixture sprayed on fruit or foliage, a smooth and uniform deposit of unusual magnitude of the insecticidal material is obtained. The invention will be more clearly understood from the following detailed description.

The effect of cation surface-active compounds as depositing agents may be explained on the basis of electrokinetic phenomena. Emulsified oil globules, as well as wet leaf surfaces, normally possess negative electrostatic charges. The mineral oils are normally emulsified for spray purposes either by mechanical agitation in the spray machine

2

alone or by such agitation and addition of oil-soluble emulsifiers. Such emulsifiers may comprise alkyl sulfonates and sulfates such as petroleum sulfonic acids and their oil-soluble sodium, potassium, or ammonium salts; fatty and naphthenic acid soaps; certain fatty acid esters of polyhydric alcohols, polymerized animal and vegetable oils and nonionic emulsifiers such as monostearyl, lauryl, and oleyl ethers of polyethylene glycol. Most of these commonly used agents are anion-active and some few are electrically neutral. They therefore either further increase the negative potential on oil globules and leaf surfaces or else have no, or but slight, effect on the electrostatic charge. The magnitude of the negative charge is directly related to the stability of the emulsion on the leaf and, consequently, emulsions containing conventional emulsifiers do not readily break to deposit the insecticidal material. In keeping therewith, I believe the effectiveness of the cation surface-active compounds as depositing agents to be due to a reduction in the negative charge or the establishment of a slight positive charge on the emulsified oil globules and a consequent reduction in the stability of the emulsion when in contact with the negatively charged leaf. However, as will be explained later, the quantity of cation-active additives must be kept below a certain maximum in order to be effective for increasing deposits of the insecticidal material. If quantities of the additives above the predetermined maximum are employed, the additives are ineffective as depositing agents. The critical feature of the quantity added is believed to be due to such a complete reversal of the charge on the oil globules when more than certain amounts are added that an emulsion results of positively charged oil globules of sufficient stability to be carried off by the water despite the attraction offered by the opposite charge of the leaves.

It follows, therefore, that less than an emulsifying amount of cationic additive should be employed, i. e. an amount of the additive less than that which will render an emulsion of the mineral oil insecticidal material more stable than prior to the addition of my additive. In general, effective quantities of my additive may range from about .01% to 1% by weight of the oil, depending upon the particular additive chosen. A preferred amount for several cationic surface-active compounds has been found to be about .1%. Although amounts within the aforementioned range are effective and generally below the amount required for increased emulsification

of the insecticidal material, this latter amount, or upper limit, can be readily ascertained by a demulsibility test, which is described later in Example II.

To facilitate a better understanding of the invention, it is perhaps well to first consider comparison between the wetting agents or emulsifiers of the anion type which are commonly used in spray oils. In such materials, the cation, or positively charged ion, is a metal of the alkali group and the anion, or negatively charged ion, is an organic radical containing at least one alkyl group having eight or more carbon atoms. The surface-active portion of the molecule is therefore negatively charged and is anion-active. Examples of this type are as follows:

(1) Soap:

(2) Sulfonated oil:

(3) Sulfated oil:

(4) Sulfated alcohol:

(5) Alkylated naphthalene sulfonate:

(6) Sulfonated nitrogen derivative:

If the sodium ion in the foregoing examples were replaced by a surface-active lipophilic organic radical and the negative ion by a non-surface-active hydrophilic radical such as an inorganic or small organic acid radical, a compound having reversed action would be obtained. The surface-active portion of the molecule would then be positively charged and therefore cation-active, while the relatively inactive acid portion of the molecule would be negatively charged. Thus, in order that a cation additive be usable, it must have a lipophilic cation radical and a hydrophilic anion radical. The additive should be soluble to the desired extent in either the oil or water phase, or both. In general, solubility in the oil phase is preferred for convenience. In order to facilitate solution of the cation surface-active depositing agent in the oil phase in the quantities required, it is often desirable to employ mutual solvents for said additives such as cresylic acid, ethers like mono- and di-ethylene glycol monobutyl ether; alcohols, especially those of more than 4 carbons; amines; ketones; and other polar compounds in amounts normally less than 5%, preferably 1% or less.

A preferred group of cation surface-active depositing agents applicable to the present invention are the onium compounds. The onium compounds, otherwise known as onium salts, or bases, contain a nuclear atom such as nitrogen, phosphorus, arsenic, oxygen, sulfur, selenium, antimony, and tin, which, for simplicity, may hereinafter be referred to as "X." For the instant purpose, at least one suitable organic radical and an acid anion or hydroxyl ion are attached to the nuclear atom X, the rest of the valences being satisfied with hydrogen atoms in a manner analogous to ammonium.

A suitable organic radical contains a lipophilic group such as, and preferably, a hydrocarbon

group of at least eight carbon atoms. The organic radical may also contain a chain comprising solubilizing or hydrophilic groups interrupting said chain or attached thereto. For example,

5 the organic radical may be a hydrocarbon or substituted hydrocarbon directly attached to the nuclear atom X, or any such groups joined to X through an oxygen or nitrogen atom attached to X by a lower hydrocarbon or substituted hydrocarbon group. Any of the otherwise unplaced hydrogen atoms bound to the nuclear atom or the nitrogen atom in the chain of the organic residue may be replaced by lower hydrocarbon or substituted hydrocarbon groups, with or without ring formation.

10 The anion may be the anion of any acid having hydrophilic properties being devoid of surface activity and being stable and inert under normal conditions of use, or it may be a hydroxyl group.

15 20 Anions such as chloride, bromide, iodide, sulfate, nitrate, acetate, propionate, malonate, malate, maleate, lactate, glutarate, etc., ions have proved especially suitable. The requirement of surface activity excludes such acids as oil-soluble sulfonic acids and the requirement of inertness excludes chromic, perboric, chloric, etc.

25 Of these onium compounds, the quaternary ammonium and phosphonium, and ternary sulfonium salts have been found to be particularly effective. The quaternary ammonium and phosphonium compounds may be represented by the general formula:

wherein X stands for nitrogen, or phosphorus; R is a hydrocarbon or substituted hydrocarbon

40 or acyl group directly attached to X, or any such groups joined to X through an oxygen atom or nitrogen atom attached to X through a hydrocarbon or substituted hydrocarbon group, R containing a terminal hydrocarbon group of at least 45 eight, and preferably at least ten, carbon atoms; Z is a hydrophilic anion; and R₁, R₂, and R₃ are radicals selected from the group consisting of hydrogen, alkyl, aryl, substituted alkyl or aryl radicals, two of which may form a heterocyclic, 50 aromatic, or alicyclic ring comprising X.

As examples of the group of compounds represented by this general formula, the following compounds may be employed in accordance with the invention:

55 1. Trimethyl octadecyl ammonium bromide, $\text{CH}_3-(\text{CH}_2)_{16}-\text{CH}_2-\text{N}(\text{CH}_3)_3\text{Br}$ is typical of a group of effective compounds in which one or more of the three methyl groups may be replaced by the following: ethyl, propyl, butyl, phenyl, or 60 amyl; or in which the octadecyl group may be a hydrocarbon of greater or lesser number of carbon atoms, but not less than eight and preferably greater than ten, or in which the bromide radical may be replaced by a chloride, iodide, acetate, sulfate, nitrate, etc., substituent. Thus, for example, cetyl trimethyl ammonium chloride ($\text{C}_{16}\text{H}_{33}(\text{CH}_3)_3\text{NCl}$).

65 2. Fatty acylated nitrogen bases and alkylated pyridine derivatives: Many of these materials are insoluble in water but are made soluble by acidulating the water.

70 Pyridinium salts may be prepared by reacting alkyl halides such as cetyl bromide with pyridine:

When this is added to water, the following reaction takes place:

3. Triethyl hexadecyl phosphonium bromide, $(C_2H_5)_3-P-(Br)C_{16}H_{33}$, dodecyl-trimethyl-p-hydroxyphosphonium bromide, $C_{12}H_{25}(CH_3)_3PBr$, or similar compounds.

4. Lauryl quinaldinium bromide:

5. Quaternary salts may be illustrated by the quaternary hydrochloride salt of diethyl aminoethyl oleyl amide, which comes under the following general formula:

wherein

is oleyl, but may also be, for instance, lauryl, myristyl, stearyl, etc., and R'' represents hydrogen, alkyl, aryl, or substituted alkyl or aryl radicals, and Z is a hydrophilic acid anion or hydroxyl ion.

Also found effective for the purpose of this invention are the ternary sulphonium salts which are similar except for the lesser valence of the nuclear atom to the quaternary ammonium and phosphonium salts described under the above general formula. The compound,

or other tetravalent sulfur compounds such as di-ethyl octadecyl sulphonium chloride

may be mentioned as illustrative of suitable sulphonium salts.

A preferred group of cation surface-active depositing agents may be prepared from the basic condensation products of organic carboxylic acids and amino-alcohols or diamines, or similar compounds having a lipophilic group of at least eight carbon atoms and being cation surface-active wetting agents.

This type of basic compound forms salts by reaction with hydrophilic acids, for example monobasic acids, such as hydrochloric and hydrobromic acid, acetic acid, propionic acid, etc., dibasic acids, such as malonic, malic, maleic, glutaric, etc., or, under proper conditions, with alkyl or aryl substituted mineral acids, which salts are cation-active. These basic compounds may be used as their salts in the present invention.

These basic compounds, which may be used to form the cation surface-active compounds of the present invention, may be designated by the general formula

wherein R is a hydrocarbon or acyl group containing a terminal hydrocarbon group of at least

eight and preferably ten carbon atoms, depending on the number and strength of the hydrophilic groups in the molecule, and which may contain non-functional substituents; and R_1 and R_2 are hydrogen or hydrocarbon radicals such as hydrogen, alkyl, aryl, aralkyl, etc., radicals, which may contain hydroxy or alkoxy radicals, halide atoms, etc.

Below are several groups of these basic compounds, which are given here merely by way of illustration:

1. Compounds of the type

2. Compounds of the type

Especially suitable compounds for my purpose are the salts of hydrophilic acids, e. g., malic acid, and the basic condensation products of high molecular weight carboxylic acids or mixtures of different high molecular weight carboxylic acids, e. g. palmitic and stearic acids, with alkanol amines. Thus, for example, the salt of malic acid and the acid amides produced by condensing a mixture of palmitic and stearic acid with ethanol ethylene diamine is particularly effective for my purpose. This salt will for convenience, be referred to hereinafter as the malate of

EXAMPLE I

The effectiveness of the depositing agents was determined under conditions simulating field practice. Spray oils to be tested both with and without the herein described depositing agents were emulsified with water in a small field-type spray machine capable of operating at spraying pressures up to 1000 lbs. Numerical evaluation of the spray deposits for the various oils and additives tested was obtained by spraying weighed four-ounce oil sample bottles, the sides of which had been coated with a thin layer of beeswax. The bottles were weighed to the nearest $\frac{1}{16}$ milligram on an analytical balance before spraying, and again after spraying, and allowing sufficient time to elapse so that all water from the spray had evaporated. The drying was expedited by placing the bottles in a stream of dust-free air. The area of the side of the four-ounce sample bottles averaged close to 150 sq. cm., and, since they were sprayed in sets of 3 for each test, the following equation can be derived:

$$D = \frac{W \times 1000}{150 \times 3} = 2.22W$$

60 where D is the average deposit in micrograms per square centimeter and W is the total spray residue on three bottles in milligrams.

The depositing agents tested as shown in the table below were tested under the following conditions:

Oil concentration, per cent	1.67
Pressure in the spray machine, lbs./sq. in.	500
Circulation time in seconds of the insecticidal composition in the spray machine	30
Spray nozzle orifice diameter, inches	$\frac{1}{64}$
Distance spray nozzle to the sample bottle, feet	6
Exposure of sample bottles to spray, sec.	6
Water hardness P. P. M. as $CaCO_3$	130

R.² Commercially available cation surface-active emulsifiers whose cation active properties were determined by cataphoresis, employing a method similar to that described in the transactions of the Faraday Society, vol. 36, pages 5-15, 1940, by H. A. Abramson, under title of "Microscopic method of electrophoresis and its application to the study of ionogenic and nonionogenic surfaces."

EXAMPLE II

In order to determine the amounts of cationic additive which would increase the emulsification of spray oil over that without any additive and thus be undesirable in accordance with the instant invention, the following tests were performed. Samples of the spray oils with different amounts of the malate of

(i. e. the salt of malic acid and the acid amides produced by condensing a mixture of palmitic and stearic acids with alkanol ethylene diamine), a cation surface-active compound, were emulsified in the laboratory spray apparatus as described above. For each test, 250 ml. of emulsion were removed from the spray tank, placed in a modified Cassia flask, and the oil allowed to separate for an hour. After standing for this period, a 50 cc. sample of the water layer was removed from the flask with a pipette and placed in a Babcock bottle and centrifuged to remove the remaining oil which had not separated or which had not been demulsified by standing. The percent of oil separated by centrifuging for the various samples tested was measured, with results as shown in the table below:

Emulsifying conditions

Oil dosage, per cent concentration¹..... 1.67
Pressure, lbs./sq. in..... 500
Circulation time, sec..... 30

¹ Oil contained .2% cresylic acid by volume as a mutual solvent for the depositing agent.

Results

Sample Number	Grams of the malate of C ₁₅ and 17H ₃₁ and 35C=O—NH—CH ₂ CH ₂ NHCH ₂ CH ₂ OH per 100 ml. oil	Percent Oil Separation from Water Layer by Centrifuging

The attached drawing shows the amount of deposit obtained with the spray oil containing various amounts of the malate of

under test conditions as described in Example I above.

20 It will be understood that the insecticidal compositions of my invention may contain other additives, such as antipenetrants like glyceryl oleate, glyceryl mono-oleate, aluminum naphthenate, visco resins, aluminum stearate, triethanolamine, cottonseed oil and similar fatty oils, etc., spreading agents such as blood albumin and/or with other known depositing agents like ketones, etc.

25 The cation surface-active depositing agents which have been described in the foregoing are merely illustrative of compounds useful for my purpose. It will be understood that the compounds meeting the tests described herein as to operativeness for my purpose and equivalents are included within the scope of the invention.

30 While I have advanced certain theories of operation for my newly invented depositing agents for insecticidal materials, it will be understood that I do not limit myself to any such theory of operation set out, but only to the invention as set out in the following claims.

I claim as my invention:

35 1. An insecticidal composition essentially comprising a mineral oil, and insecticidal toxicant, and between about 0.01% and about 1.0% (by weight of the oil) of a cation surface-active depositing agent, said composition being capable of forming an unstable emulsion with water.

2. An insecticidal composition essentially comprising a mineral oil, and insecticidal toxicant, and a cation surface-active depositing agent in an amount of the order of about 0.1% by weight

of the oil, said composition being capable of forming an unstable emulsion with water.

70 3. An insecticidal composition essentially comprising a mineral oil, and insecticidal toxicant, and between about 0.01% and about 1.0% (by weight of the oil) of a salt of a hydrophilic acid and the acid amide condensation product of a fatty acid with an alkanol amine, said composi-

tion being capable of forming an unstable emulsion with water.

4. An insecticidal composition essentially comprising a mineral oil, and insecticidal toxicant, and between about 0.01% and about 1.0% (by weight of the oil) of the malate of the condensation product of ethanol ethylene diamine and a mixture of stearic and palmitic acids, said composition being capable of forming an unstable emulsion with water.

5. An insecticidal composition essentially comprising a mineral oil, and insecticidal toxicant, and between about 0.01% and about 1.0% (by weight of the oil) of a cation surface-active depositing agent and a minor amount, based on the weight of said oil, of a mutual solvent for said cation surface-active depositing agent, said composition being capable of forming an unstable emulsion with water.

6. An unstable insecticidal emulsion of a mineral oil in water essentially comprising said mineral oil, an insecticidal toxicant, water, and between about 0.01% and about 1.0% (by weight of the oil) of a cation surface-active depositing agent.

KENNETH E. MAXWELL.
